UNITED STATES PATENT OFFICE.

FALCONER O'BRIEN, OF DETROIT, MICHIGAN.

SEAT-SPRING.

1,183,400.

Specification of Letters Patent. Patented May 16, 1916.

Application filed August 21, 1914. Serial No. 857,943.

To all whom it may concern:

Be it known that I, FALCONER, O'BRIEN, a citizen of the United States of America, residing at Detroit, in the county of Wayne 5 and State of Michigan, have invented certain new and useful Improvements in Seat-Springs, of which the following is a specification, reference being had therein to the accompanying drawings.

10 The invention relates to spring construction, and resides in the novel formation of the frame, in the novel manner of attaching the springs to the frame, in the peculiar connection between the seat covering and the 15 frame; and further, in certain combinations, arrangements and details of construction as will more fully hereinafter appear.

In the drawings.—Figure 1 is a side elevation of a spring construction embodying 20 the invention; Fig. 2 is a sectional plan view; Fig. 3 is a perspective view illustrating a detail of construction; Fig. 4 illustrates a modification; Fig. 5 illustrates the manner of connecting the seat covering to 25 the frame; Fig. 6 is a fragmentary top plan view illustrating a modification; Fig. 7 is a perspective view of the structure shown in Fig. 6; Figs. 8, 9 and 10 illustrate another 30 modification; and Fig. 11 is a sectional view showing the modified manner of connecting the seat covering to the frame.

In spring constructions it is very desirable to have the frame carrying the springs so formed that it may be easily and cheaply 35 manufactured and yet possess the desired strength and rigidity to withstand the stresses to which the seat is subjected. It is also desirable that the seat parts be such that they may be readily assembled. With 40 the spring seat embodying my invention, not only may the parts be easily and quickly assembled, but the strength and rigidity of the structure is materially increased over spring seats now in common use.

45 Referring to Figs. 1 to 3 inclusive of the drawings, A designates the bottom frame of the spring seat, B the top frame and C the springs having their opposite ends connected to the frames A and B respectively. The 50 connection between the springs and the frame B, for the purpose of this invention may be of any well known construction. The frame A however, is a novel structure, as is also the manner of attaching the 55 springs thereto. As shown the frame A comprises an outer annular member D and cross members or bars E, the latter being

attached to the springs but in the structure illustrated in Fig. 2 not being connected to the member D. In the type of spring shown 60 the frame members D and E are of channel shaped cross-section and are connected to the bottom convolution of the spring upon opposite sides thereof. The end members of the series of springs are also secured to 65 those portions of the annular member D that extend transversely to the members E. The connection between the frame members and the springs is such as to lock the convolution to the frame member against turning movement. This is accomplished in the arrangement shown in Figs. 1 to 3 inclusive by cutting away portions F and G of one of the transversely-extending flanges, as H, 70 so as to permit a portion I of the convolution 75 of the spring to rest upon the base J of the channel and abut against the inner face of the other flange K. The cut-away portions form spaced shoulders or abutments L and M which engage the convolution. 80 In the form of the member E shown in Fig. 2, the intermediate portion N is then bent over the portion I to hold the convolutions in engagement with the spaced shoulders and the inner 85 face of the flange K, as well as to secure the convolutions to the base J.

Instead of turning down all of the portion intermediate the shoulders L and M, lugs O and P may be formed from the intermediate portion and bent over the convolution as shown in Fig. 3. In Figs. 6 and 7 the flange is provided with a cut-away portion Q, the portion R formed by cutting away the metal serving as a retainer. 95

In Fig. 8 a lip a is struck out from the bottom of the channel member, while the flange b of the channel member is provided with cut-away portions or recesses c d to receive the convolutions e of the spring. 100

In assembling the structure shown in Figs. 8, 9 and 10 the recesses c d are formed therein and the flange a struck up from the bottom and arranged to permit the convolutions of the spring to be inserted between 105 it and the flange f of the channel member. The lip a is then bent over the spring, as shown in Fig. 8. In each of the spring constructions shown a portion of the convolution not only is secured to the base of the frame member, but is held against the inner face of the flange. The convolution is also clamped against the spaced abutments or shoulders and as the corners thereof

form in effect knife-edge bearings, when the convolution is clamped against these corners the latter securely grip the convolution and prevent it from turning upon the frame member. By anchoring the convolution to the frame member against turning movement, not only is the rigidity of the connection between the springs and the frame members materially increased but 10 also the rigidity and strength of the frame is increased.

When the outer frame member D is formed of channel cross-section, if desired the lower edge T of the seat covering U may 15 be clamped to the frame by turning down the flange H, as shown in Fig. 5. When the lower edge of the covering is so anchored the frame member B is preferably connected to the convolutions of the springs by 20 turning down a part only of the portion of the flange H intermediate the shoulders L and M, as shown in Fig. 3, since this allows the part V intermediate the lips O and P to be bent over the lower edge of the covering U, as shown in Fig. 5. Instead of bending down the flange H, the flanges of the channel outer member may be bent together to secure the lower edge of the covering thereto, as shown in Fig. 11.

30 In Fig. 4 the member A' is formed of heavy wire and the springs are secured to the member A' through the medium of cross members B' which are of a construction similar to the members E with the exception that the ends of the members B' are provided with lips C' that are bent around the wire A' to connect the latter to the cross members.

40 While I have shown and described the preferred forms of the invention I do not desire to limit my protection to the particular structures illustrated, but consider the invention of sufficient scope to embody various modifications. Also while I have described the invention as embodied in the bottom frame, it will of course be understood that my improved structure may be employed for either the top or bottom frames of the seat spring.

45 50 What I claim as my invention is:—

1. In a spring construction, a member composed of a body portion, a longitudinal flange extending transversely from the body portion, and a spring having a convolution resting upon the body portion and contacting with the flange at a plurality of spaced points, said member having a portion engaging the convolution for securing the latter to the body portion and holding the 55 convolution in engagement with the flange.

2. In a spring construction, a member composed of a body portion and a longitudinal flange extending transversely there-

from, said flange having spaced shoulders, and a spring having a convolution resting 65 upon the body portion and contacting with the spaced shoulders, said member having a portion engaging the convolution for securing the latter to the body portion and holding the convolution in engagement with 70 said shoulders.

3. In a spring construction, a member composed of a body portion, a longitudinal flange extending transversely from the body portion, and a spring having a convolution resting upon the body portion and contacting with the flange at a plurality of spaced points, said member being provided with a retaining lip engaging the convolution intermediate said spaced points for 80 securing the latter to body portion and holding the convolution in engagement with the flange.

4. In a spring construction, a member composed of a body portion, and a longitudinal flange extending transversely therefrom, said flange having spaced shoulders, and a spring having a convolution resting 85 upon the body portion and contacting with the spaced shoulders, said member having a retaining lip formed thereout of engaging the convolution for securing the latter to the body portion and holding the convolution in engagement with said shoulders, said shoulders being interiorly engaged with the 90 convolution and said lip interiorly.

5. In a spring construction, a member composed of a body portion and a longitudinal flange extending transversely from the body portion, a spring having a convolution resting upon the body portion, said flange being cut away to permit the convolution to pass therethrough and to form spaced abutments, said member having a portion engaging the convolution for securing the latter to the body portion and holding the convolution in engagement with the spaced abutments.

6. In a spring construction, a member of channel cross-section, and a spring having a convolution resting upon the base of said channel member and contacting with one flange, the other flange of said member being cut away to permit the spring to pass therethrough and to form spaced shoulders, 110 said member having a portion engaging the convolution for holding the latter in engagement with the first-mentioned flange and with the shoulders of the second-mentioned flange.

115 120 In testimony whereof I affix my signature in presence of two witnesses.

FALCONER O'BRIEN.
